(57) CLAIM

The ornamental design for a shoe midsole with contrasting translucent regions, as shown and described.

DESCRIPTION

FIG. 1 is a front perspective view of a shoe midsole with contrasting translucent regions showing my new design; FIG. 2 is a side view thereof; and, FIG. 3 is a rear perspective view thereof.

The difference in greyscale shading between the front two claimed regions and the rear two claimed regions represents a contrast of color. The broken lines showing the remainder of the shoe are for environmental purposes only and form no part of the claimed design.
